UNITED STATES PATENT OFFICE

RALPH L. BROWN AND WILLIAM W. ODELL, OF PITTSBURGH, PENNSYLVANIA

PROCESS FOR PRODUCING OXYGENATED ORGANIC COMPOUNDS

No Drawing.

Application filed September 21, 1927. Serial No. 221,129.

The invention relates generally to a process for treating relatively inexpensive saturated hydrocarbons or paraffins, such as petroleum products containing ethane, propane, butane, and higher hydrocarbons for conversion of such products into valuable unsaturated compounds such as olefins, that may be converted into various other valuable materials, such as alcohols, aldehydes, and the like. Such a process, broadly speaking, is old but it is the object of the present invention to improve the efficiency of the process, making it possible to utilize the original starting materials to the best advantage. It has been found impossible to completely crack paraffines or saturated hydrocarbons in a single cracking treatment and, at the same time, to produce the maximum yield of olefines from the original starting materials. Accordingly, recirculation of the uncracked paraffines through the cracking chamber is resorted to. To do this, however, it is, of course, necessary to separate the residual paraffins from the other products so that the paraffins may be returned to the cracking chamber. Since, however, corresponding olefins and paraffins having the same number of carbons, for example, propylene and propane, have substantially the same boiling point, such separation cannot be readily effected by ordinary methods such as fractional distillation, but, according to applicants' invention, may be best carried out either by hydration or by combined hydration and polymerization of the olefins to produce materials of different boiling points from the paraffins, such as alcohols, ethers and the like. After such hydration and/or polymerization of the olefins, the residual paraffins may be separated from the oxidation products and may then be recirculated through the cracking chamber.

In commercial practice when saturated hydrocarbons such as butane, propane or the like are used as raw materials in the production of alcohols and ethers, two distinct processes are generally used; one comprising the chlorination of the hydrocarbon followed by the treatment of the chlorinated product with

an alkali, the reactions being represented by Equations 1 and 2 for the production

- (1) $C_3H_8 + Cl_2 = C_3H_7Cl + HCl$
 (2) $C_3H_7Cl + NaOH = C_3H_7OH + NaCl$
 (3) $2C_3H_7(OH) - H_2O$ (distilled in presence of H_2SO_4) $= C_3H_7O.C_3H_7$

of alcohol, Equation 3 representing the generation of an ether, in this example dipropyl ether. The other method involves the cracking of the saturated hydrocarbons by the application of heat, subsequently treating the unsaturated hydrocarbons—the olefins, in particular—with acid, forming an additional product which is subsequently treated with a caustic alkali as in the above example, or hydrolyzed with steam. These processes are not direct in that reactions with acids or acid radicals and with alkalis are part of the process. These steps are eliminated in our process.

Among the objects of our invention are

- (1) To utilize saturated hydrocarbons which are available in large quantities and which are not adaptable for use as motor fuel, in the preparation of ethers, which are adaptable for use as a blending agent in the mixing of alcohols with gasolines or the like, in the production of motor fuels.
 (2) To make alcohols and ethers from saturated hydrocarbons by a continuous process.
 (3) To make low-priced raw materials for the production of synthetic esters, essential oils and the like from low-priced hydrocarbon compounds.

Briefly the process consists in cracking the saturated hydrocarbons producing unsaturated hydrocarbons such as olefins, and subsequently causing the unsaturated hydrocarbons to react with steam under pressure in the presence of a catalyst yielding alcohols, ethers, mixtures of the two, or other oxygenated products: the latter step being subject matter for our patent application Serial No. 198,202, filed June 11, 1927.

The different steps of our process are co-acting as shown in the following more complete description. For the purpose of exemplification a single saturated hydrocarbon is referred to here, namely propane. The

first step comprises passing the vaporized, gaseous, propane into a cracking apparatus in substantially a continuous stream, heating the propane therein to a cracking temperature of less than 1000 degrees C. and preferably below 900 degrees C., preferably in the presence of a catalyst such as Al_2O_3 , and conducting the undecomposed hydrocarbon along with the products resulting from cracking, which latter may include H_2 , CH_4 , C_2H_6 , C_2H_4 , and C_3H_6 , out of the cracking apparatus. The second step comprises compressing the products from the cracking apparatus with or without cooling as found necessary, 15 eliminating the H_2 and CH_4 by the liquefaction of the remaining constituents comprising the unsaturates and the homologs of CH_4 . The third step comprises introducing the recovered mixture containing the unsaturates, 20 along with steam, under pressure greater than atmospheric and preferably in the vapor phase, into a reaction chamber and causing chemical reaction to take place therein while the reacting substances are under pressure 25 greater than atmospheric and at a temperature above 100 degrees C. by the aid of a catalyst.

The fourth step comprises removing the reaction products which include an alcohol 30 or an ether or both according to conditions as described in our patent application Serial No. 198,202, from the remaining products which may include C_3H_8 , C_2H_6 , unsaturates and H_2O . When higher hydrocarbons than propane (C_3H_8) are used as raw materials there may be, and normally would be some saturated hydrocarbons higher in the series than propane. The fifth step comprises the introduction of the latter products, namely 40 and chiefly, the saturated hydrocarbons, into the cracking apparatus with the hydrocarbons used in step 1 for the production of unsaturates. It will be noted that the products thus recirculated do not include appreciable 45 amounts of hydrogen, CO_2 , CO and N_2 , which usually appear in the end products in the commercially employed methanol process.

Our reactions are carried out preferably 50 in the vapor phase and therefore it is necessary to adjust temperatures and pressures to suit the requirements of the different hydrocarbons used and reaction products made. This relation obviously is based upon the 55 vapor pressures of the different hydrocarbons, H_2O and reaction products formed. Up to the critical temperature there is a pressure above which one can not operate satisfactorily and economically in the vapor phase 60 and that pressure is the pressure at which liquefaction takes place. Above the critical temperature this definite relation does not exist.

Catalysts adaptable for use in our process 65 and the temperature-pressure relations in

carrying out the different steps of said process are discussed, alluding again to the above mentioned five steps, as follows:

In Step 1, using propane again as an example, the cracking of the latter for the production of unsaturates may be carried on at a pressure which is substantially atmospheric pressure; the reaction being substantially represented by Equation 4. 75

To carry out this reaction normally a fairly high "cracking" temperature would be required, namely 900 degrees to 1000 degrees C., but we have found that by employing suitable catalysts the reaction can be carried out at temperatures lower than otherwise with a result favorable to the production of the maximum amount of unsaturates. Aluminum oxide is one catalyst which aids in carrying this class of reactions toward completion at lower temperatures than otherwise possible. 80

It is found that at higher cracking temperatures than about 600 to 900 degrees centigrade the tendency for carbon to form as a result of cracking increases with increments of temperature; this varies in extent with the different catalysts, with the velocity of saturated hydrocarbons through the cracking apparatus and with the nature and properties of the hydrocarbon compounds used as raw materials. It seems to be a property of hydrocarbon compounds of high molecular weight to break up into molecules of lower molecular weight more readily than their homologs of lower molecular weight. 95

Upon recirculating the gases from the above named Step 5, that is, upon passing them through the cracking apparatus of Step 1, there would normally be a tendency for the concentration of H_2 , CH_4 and C_2H_6 were it not for the provision for their removal at the completion of Step 1. It will be noted that when ethyl alcohol, ethyl ether or mixtures are the desired end products, it is essential to produce in Step 1 the maximum amount of C_2H_4 . The latter gas being produced from C_2H_6 as well as from the higher paraffins it becomes desirable to effect as large a conversion of C_2H_6 into C_2H_4 as possible in Step 1. It appears that in the cracking of C_2H_6 according to reaction Numbered 5 the time of reaction ordinarily is slow 110 at 675 degrees. 115

to 800 degrees centigrade without a catalyst. 120 When cracked at temperatures materially higher than the latter temperature there are also formed C , CH_4 and other products; at such temperatures the conditions are not favorable for the maximum yield of C_2H_4 , 130 therefore it becomes essential to crack the

paraffins at as low a temperature as possible in order to produce C_2H_4 and to crack C_2H_6 in the most economic manner. This we accomplish by the use of catalysts, employing a temperature preferably below 900 degrees centigrade for cracking C_2H_6 and about 800 degrees centigrade for cracking propane and butane. Equation 5 shows that 1 volume of C_2H_6 yields 2 volumes of gas by an endo-thermic reaction. Obviously any increase in the concentration of H_2 or increase in pressure on the system in Step 1, namely in the cracking apparatus, will normally tend to reverse the reaction of Equation 5 and decrease the yield of C_2H_4 . Accordingly we prefer to crack the C_2H_6 at pressure not greatly in excess of atmospheric, realizing that low pressures during cracking favor the maximum C_2H_4 yield, and we prefer to have the minimum amount of H_2 in the recirculating gases. Natural gas sometimes contains 15 per cent or more of C_2H_6 which latter can readily be converted by the herein described process to C_2H_5OH , $C_2H_5OC_2H_5$ or mixtures of the two; the H_2 formed can, with beneficial results, be introduced into the remaining CH_4 gas if desired: the latter mixture not being used in our process.

When the cracking temperatures employed in Step 1 are sufficiently high and when the lower monohydric alcohols or simple ethers are the final products sought, the process is more simple than otherwise, since at temperatures at which C_2H_6 decomposes the higher members of the homologous series also decompose; the higher members of the series decomposing normally at lower temperatures than C_2H_6 . When using as raw materials hydrocarbons of higher molecular weight than C_2H_6 and C_3H_8 there are numerous factors to consider and control. For example, it is possible to crack C_6H_{14} with the production of an appreciable amount of amylene (C_5H_{10}) or, at higher temperatures or under different conditions crack it more completely recovering chiefly C_2H_4 , C_3H_6 and C_4H_8 , or still more completely as already discussed. When a mixture of hydrocarbons is employed as a base material and cracked under conditions favorable for the formation of a series of olefins such as C_2H_4 , C_3H_6 , C_4H_8 , C_5H_{10} etc., the separation of unsaturates from the paraffins which accompany them is not an easy matter without the destruction of one or the other series of hydrocarbons. The boiling points of the lower members of the paraffin series are substantially the same as those of the olefin series comparing hydrocarbons having the same number of carbon atoms in each case. Ethylene has a low critical temperature and therefore can readily be separated from its corresponding paraffin—(C_2H_6)—or from other members of the two series. Propylene and butylene can not readily be com-

pletely separated respectively from propane and butane by physical means. Therefore in producing alcohols and ethers of higher molecular weight by our process it is sometimes found desirable or economic to allow one or more members of the paraffin series to pass along with the unsaturates into the reaction chamber of Step 5 even though they do not enter into chemical reaction with steam therein. Upon completing the reactions of Step 5 and formation of alcohols and ethers it is found that the properties of the latter substances are so different from those of the paraffins that the latter can readily be separated from the former and again introduced into the cracking apparatus of Step 1. Since, upon cracking, the paraffins of high molecular weight yield besides olefins and H_2 , paraffins of lower molecular weight it is desirable, in operating a multiplicity of units each at different cracking temperatures to conduct the particular paraffins from Step 5 to the particular cracking apparatus wherein it can be most effectively used. For example, it would hardly be economical in most cases, to circulate C_2H_6 and C_3H_8 when it is desirable to produce C_4H_8 in the cracking step and C_4H_9OH in the reaction chamber. It would be better under these conditions to conduct the C_2H_6 and C_3H_8 to cracking apparatus wherein it is desirable to produce C_2H_4 . It will be noted that the paraffins can readily be separated from the alcohols and ethers and from one another, hence it is possible to use them most effectively in recirculation; in general it is preferable to circulate the paraffins residual to Step 5, in the production of higher alcohols and ethers in the reaction chamber of Step 5, to a cracking apparatus adapted and operated for the production of olefins suitable for the production of lower alcohols and ethers. This step brings in the inter-relation of multiple units in the separate production of a multiplicity of ethers and alcohols.

Referring again to Step 1, the cracking process, it is found that whereas C_2H_6 can readily be cracked yielding C_2H_4 and H_2 at elevated temperatures, there is a strong tendency for a recombination and formation of C_2H_6 at lower temperatures, namely at temperatures somewhat above 100 degrees C. This fact explains the different and widely varied results reported by different investigators of the C_2H_6 cracking reactions at different temperatures. Rapid cooling at the end of Step 1 obviates this to a certain extent. The H_2 is removed in our process before the cracked products enter the reaction chamber or are again heated, otherwise there would by a union of H_2 and C_2H_4 seriously decreasing the efficiency of the process. The removal of H_2 at this point is an important step.

Alluding now to Step 2, the compressing and liquefying phase of the process, we be-

lieve we have found commercial application for the phenomena that the members of the olefin series of high molecular weight polymerize more readily than those of lower molecular weight; this phenomena not being limited to that particular series of unsaturated hydrocarbons. Thus in the compressing stage it is possible to eliminate some of the unsaturated hydrocarbons having a molecular weight higher than that of C_2H_4 , namely higher than 28, from the other constituents from Step 1, by polymerization. Since in reactions of the latter type a decrease in volume accompanies polymerization increments in pressure tend to hasten the reactions. We have succeeded in polymerizing isobutylene at 380 degrees C. at 70 atmospheres pressure; and by the aid of catalysts such as $AlCl_3$, PCl_5 and others, this reaction can be carried out at lower temperatures and lower pressures. The element of time is an important factor in such reactions, having greater significance at the lower temperatures and pressures than at higher ones. Ethylène also can be polymerized in a similar manner at slightly higher temperatures.

Upon polymerizing these substances we got end products comprising paraffins, cycloparaffins and unsaturates. It will be noted that the products from Step 1 contain H_2 as well as unsaturated hydrocarbons and we find that it is possible to cause H_2 to combine preferentially with the unsaturates of higher molecular weight than 28 by controlling the temperatures and pressures in Step 2. Thus we have in Step 2, two possible and distinct types of reactions under control, namely polymerization and hydrogenation, the former being represented by Equation 6, the latter by Equation 7.

When those paraffins are cracked in Step 1 which yield olefins higher in the series than C_2H_4 it is a simple matter to separate them from the latter and convert them to saturated hydrocarbons adaptable for lubricating stock or other use by combining the reactions shown by example in Equations 6 and 7, using the hydrogen produced as a by-product in the cracking phase,—Step 1. The latter reactions may be carried out in the liquid phase using olefins higher in the series than C_2H_4 taking advantage of the known properties of catalysts to speed them. Finely divided or reduced metals are known to catalyze hydrogenation and salts or compounds containing acid radicals comprise one class of substances which catalyze polymerization.

Referring again to Step 2; regardless of whether or not polymerization and hydrogenation are induced in this step the olefins or other unsaturates desired for use in Step 2, are separated as completely as is economical.

ly possible from the remaining constituents by any suitable means, and are then compressed to the pressure desirable for their use in Step 3, heated when necessary and introduced along with H_2O , into the reaction chamber of Step 3. In the latter step the reactions, already alluded to as subject matter for a previous patent application, are of a nature represented by Equations 8, 9, 10, 11, 12, and 13.

According to the proportion and concentration of the reacting substances, the velocity through reaction chamber, temperature and pressure therein and catalyst used, the exact nature of the end products will vary. In commercial operation these variables are controlled just as the cracking reactions of Step 1 are controlled, with a view to making the preferred end product or mixture of products. The end products from Step 3 are separated from gases which may comprise paraffins and some unsaturates and are separated from each other when so desired using known methods for such separation. The gases are conducted to the cracking apparatus for Step 1.

The products leaving the reaction chamber are hot and under considerable pressure and in reducing the temperature and cooling, an engine, multiple stage turbine, other power generating unit or the like may be used thus converting the heat energy into mechanical energy and simultaneously fractionally condensing, and cooling the reaction products. The exhaust pressure can be so controlled that only products having boiling points above certain limits can condense. In other words the fractional condensation in this manner is controlled by knowledge of the vapor pressure—(the temperature-pressure relations) of the different alcohols and ethers. Any suitable means of fractional separation may be used.

Referring to Equation 13, we have found, as shown, that under some conditions there is a tendency for a certain amount of polymerization accompanying the reaction of olefins with steam, particularly in the presence of a catalyst. Utilizing this reaction it is possible to make higher alcohols or ethers from olefins of low molecular weight. This in turn simplifies the cracking process making it possible to crack at a temperature which will destroy the higher olefins and yield chiefly olefins of lower molecular weight which latter can more readily be separated from the products accompanying it resulting from cracking. We have found that certain

catalysts, including mixed catalysts, aid in producing such molecular rearrangement and have successfully used salts containing an inorganic acid radical such as $Al_2(SO_4)_3$.
 5 A suitable mixed catalyst for use in the reaction chamber comprises Al_2O_3 and a salt containing an acid radical, for example

- 10 In carrying out the different steps of our process we find that the most economic conditions for the production of the end products and various intermediate products are not always identical with those favoring 15 maximum yield per unit of raw material. For example in cracking hydrocarbons for the production of unsaturates it is sometimes an advantage to conduct the cracking at high temperatures, up to 1000 degrees C. or even 20 higher, the yield of unsaturates being lower per unit of hydrocarbon used in this instance, but the total production of unsaturates per unit of time may be higher because of conditions relating to heat transfer rates 25 at the different temperatures and other factors. We therefore do not care to limit ourselves with respect to temperatures employed in the cracking phase, Step 1. It is believed that cracking processes are old in the art 30 and therefore this step is not broadly claimed as our own. In the cracking phase any catalyst may be used which is known to catalyze the reactions which yield unsaturated hydrocarbons.

35 When using hydrocarbon compounds which are not gaseous at atmospheric pressure at temperatures normal or somewhat above normal, it is possible to obtain good results in cracking by introducing them as a fine mist, namely in the atomized state into the cracking chamber. In the example cited in the description of our process propane was the hydrocarbon compound used and it happens to be a gas under normal conditions.

40 The cracking chamber has not been described because it is not claimed herein as new and because different types of cracking apparatus which are not new may be used. A refractory lined chamber having an inlet and an outlet traversable from said inlet to said outlet by a fluid, having refractory contact-material arranged in the path of said fluid, having means for introducing hydrocarbon compounds therein and having means for heating said contact material, which latter material may be or may contain catalytic material, will function as a cracking chamber in carrying out Step 1.

45 The products resulting from cracking may be separated into fractions and selected fractions only admitted to chemical reaction with steam, or all of the unsaturates thus made may be used together in the production of oxygen-containing compounds. We find that at about 40 to 50 atmospheres pressure

and at a temperature above 205 degrees C. only those olefins higher in the series than C_6H_{10} will condense upon subsequently cooling and maintaining the pressure. C_6H_{10} will condense at approximately 200 degrees C., or lower. Upon subsequently cooling in the same manner to about 150 degrees C. C_4H_8 will condense. At 97 degrees C. C_3H_6 condenses at about 50 atmospheres pressure; C_2H_4 remaining in the gaseous state at all pressures until the temperature is reduced to approximately 10 degrees C. It is thus possible to separate these components and polymerize and hydrogenate individual components as desired, using selected olefins for reaction with steam in the subsequent step. The hydrogenation and polymerization are conducted in the vapor phase for the olefins lower in the series than C_7H_{14} .

50 The temperatures and pressures optimum for the reactions of unsaturates with steam in the formation of oxygen containing compounds vary for the different compounds formed. These gas reactions, exemplified in Equations 8 to 13, are accompanied by a decrease in volume and it is evident that an increase in pressure favors the reactions; the pressure is limited only because of cost or mechanical conditions. Usually in working at 200 degrees to 400 degrees C. suitable pressures are those which will allow the reacting substances to remain in the gaseous state. Water at 200 degrees C. is in the gaseous state at pressures less than about 16 atmospheres whereas at 330 degrees C. it is in the gaseous state up to about 130 atmospheres. Consideration is given to the vapor pressure of the reacting substances and their partial pressures in a given mixture and an economic temperature and an economic pressure are selected as optimum for a given set of conditions.

55 When highly superheated steam is used in the reaction chamber the temperature of the unsaturated hydrocarbons introduced therewith may be lower than otherwise. Thus when making alcohols, when the quantity of steam is in large excess of the amount of the olefins used, this method of operating is sometimes advantageous.

60 We realize fully that with complete polymerization of unsaturated hydrocarbons the resulting products will ordinarily possess the properties of saturated hydrocarbons and therefore will not readily combine with H_2O forming oxygenated products; however we find that under the influence of mixed catalysts and under the conditions which we employ there is a production of a certain amount of higher alcohols from simpler unsaturates. We believe the explanation of the formation of the latter alcohols as described is found in the simultaneous hydration and polymerization. These reactions are conceivable as a direct union of carbon to carbon

co-occurring with the hydration of adjoining carbon atoms of the ethylene-linkages involved, or as resulting through molecular rearrangement simultaneous with hydration reactions.

We find that iron, preferably on a carrier, polymerizes C_2H_4 at 360 degrees centigrade even at atmospheric pressure. Higher pressures favor this class of reactions. At slow velocity and at 425 to 450 degrees centigrade decomposition takes place when ethylene alone is passed over iron catalyst at atmospheric pressure, carbon being deposited. Using pressures above atmospheric as in our process and carrying out these reactions in the presence of steam the decomposition effect with the accompanying deposition of carbon is minimized.

We claim:

- 30 1. A cyclic process for treating saturated hydrocarbons for conversion into valuable synthetic products, including alcohols and ethers with the recovery and recirculation of residuals of the reaction, which comprises first cracking said hydrocarbons in a cracking chamber and producing therefrom unsaturated hydrocarbons; second subjecting said unsaturated hydrocarbons under pressure greater than atmospheric to the action of H_2O in the presence of a solid catalyst adapted to catalyze hydration reactions, at a temperature above 100 degrees C., thereby forming corresponding oxygenated compounds, subsequently condensing the oxygenated products formed and conducting the gaseous non-oxygenated residuals of reaction comprising largely saturated hydrocarbons back into a cracking chamber and into cracking reactions.
- 40 2. A cyclic process for treating saturated hydrocarbons for conversion into valuable synthetic products, including alcohols and ethers with the recovery and recirculation of residuals of the reaction, which comprises first, cracking said hydrocarbon compounds in a suitable cracking chamber by the application of heat, and producing thereby said unsaturated hydrocarbons; second compressing and separating them along with saturated hydrocarbons having similar boiling points from H_2 and CH_4 , produced during said cracking; third: subjecting them along with the separated saturated hydrocarbons under pressure greater than atmospheric and at a temperature above 100 degrees C. to the action of H_2O in the presence of a solid catalyst adapted to catalyze hydration reactions but incapable of entering into said reactions; thereby forming from them the corresponding oxygenated compounds; fourth, expanding the reaction products to a lower pressure, condensing the oxygenated products formed, separating them from the gaseous residuals of reaction including largely paraffins, and finally conducting said gaseous residuals back

into a cracking chamber and cracking reactions.

3. A cyclic process for treating saturated hydrocarbons for conversion into valuable synthetic products, including alcohols and ethers with the recovery and recirculation of residuals of the reaction, which comprises first, cracking said hydrocarbon compounds in a suitable cracking chamber by the application of heat, producing thereby said unsaturated hydrocarbons; second, compressing the resulting products and separating therefrom a paraffin and an olefin hydrocarbon having substantially the same boiling points; third, subjecting said separated hydrocarbons under pressure greater than atmospheric, at a temperature above 100 degrees C. to the action of H_2O in the presence of a solid catalyst adapted to catalyze hydration reactions, in a suitable reaction chamber, thereby forming a corresponding oxygenated compound from said olefin; fourth, condensing the said oxygenated product formed, separating it from the gaseous residuals and finally conducting at least a portion of said gaseous residuals back into a cracking chamber and cracking reactions.

4. A cyclic process for treating saturated hydrocarbons for conversion into valuable synthetic products, including alcohols and ethers with the recovery and recirculation of residuals of the reaction, which comprises first, cracking said hydrocarbons in a suitable cracking chamber by the application of heat, producing reaction products containing said unsaturated hydrocarbons; second, separating unsaturated hydrocarbons from said reaction products by preferential condensation; third, subjecting said unsaturated hydrocarbons to the action of predetermined amounts of water under pressure greater than atmospheric and at a temperature higher than 100 degrees C. in the presence of a catalyst adapted to catalyze hydration reactions in a suitable reaction chamber, causing direct chemical reaction to occur between said water and said separated unsaturated hydrocarbons resulting in the formation of the corresponding oxygen-containing compounds and fourth, removing said oxygen-containing compound from reaction residuals, conducting at least a portion of said residuals back into a cracking chamber and cracking reactions; the relative amounts of alcohols and ethers formed varying with and dependent upon the relative concentration of the reactants in said reaction chamber, a high concentration of said water favoring the formation of a high relative amount of alcohols and vice versa.

5. A cyclic process for treating saturated hydrocarbons for conversion into valuable synthetic products, including alcohols and ethers with the recovery and recirculation of residuals of the reaction, which comprises, first, cracking said hydrocarbon compounds

- in a suitable cracking chamber by the application of heat producing thereby a product containing a plurality of said unsaturated hydrocarbons; second, separating a plurality of selected olefins from said product by liquefaction; third, subjecting said selected olefins to the action of H_2O under pressure greater than atmospheric, at a temperature above 100 degrees C., in the presence of a solid catalyst adapted to catalyze hydration reactions in a suitable reaction chamber, thereby forming corresponding hydration products; fourth expanding and cooling the products of reaction, separating said hydration products from gaseous non-oxygenated residuals by liquefaction and finally conducting at least a portion of said residuals back into a cracking chamber and cracking reactions. 6. A cyclic process for treating saturated hydrocarbons for conversion into valuable synthetic products, including alcohols and ethers with the recovery and recirculation of residuals of the reaction, which comprises first, cracking said hydrocarbon compounds in a cracking chamber in the presence of a catalyst of the type adapted to catalyze cracking reactions with the minimum formation of carbon, by the application of heat, producing thereby a product containing H_2 and said unsaturated hydrocarbons; second, separating from said product by fractional condensation those selected unsaturated hydrocarbons adapted for making particular oxygen-containing compounds; third subjecting said selected unsaturated hydrocarbons to the action of H_2O under pressure greater than atmospheric, at a temperature above 100 degrees C. in the presence of a solid catalyst adapted to catalyze hydration reactions in a reaction chamber, causing direct chemical reaction to occur between them and said H_2O forming the corresponding oxygen-containing compounds, fourth, cooling the products of reaction, separating therefrom, said particular oxygen-containing compounds; and finally conducting at least a portion of the residuals of reaction back into a cracking chamber and cracking reactions. 7. A cyclic process for treating saturated hydrocarbons for conversion into valuable synthetic products, including alcohols and ethers with the recovery and recirculation of residuals of the reaction, which comprises cracking said hydrocarbon compounds in a cracking chamber by the application of heat, producing a product containing H_2 and unsaturates including olefins; compressing said product, exposing it to a catalyst adapted to catalyze the polymerization and hydrogenation of unsaturated hydrocarbons while under pressure and at a temperature above 100 degrees C. and causing preferential polymerization and hydrogenation of unsaturates having a molecular weight higher than 56 by limiting said temperature, said pressure and the time of contact of said product with said catalyst to units unfavorable for the polymerization and hydrogenation of unsaturates having lower molecular weights; separating olefins from the polymerized and hydrogenated product and subjecting them to the action of H_2O under pressure greater than atmospheric at a temperature higher than 100 degrees C. in the presence of a solid catalyst adapted to catalyze hydration reactions in a reaction chamber, causing direct chemical reactions to occur between them and said H_2O , forming the corresponding oxygen-containing compounds, expanding and cooling the reaction products, separating therefrom said oxygen-containing compounds and conducting the remainder of said reaction products to a cracking chamber for the further production of olefins. 8. A cyclic process for treating saturated hydrocarbons for conversion into valuable synthetic products, including alcohols and ethers with the recovery and recirculation of residuals of the reaction, which comprises cracking said hydrocarbon compounds in a cracking chamber by the application of heat, producing a product containing H_2 and said olefins; compressing said product and separating said olefins therefrom; subjecting said separated olefins to the action of H_2O under pressure greater than atmospheric at a temperature higher than 100 degrees C. in the presence of a solid catalyst adapted to catalyze hydration reactions in a reaction chamber, causing chemical reaction to occur forming a mixture of ethers and alcohols containing a large or small percentage amount of said alcohols accordingly as the amount of said H_2O used in said reaction chamber is large or small relative to the amount of said olefins used; subsequently cooling and fractionally condensing said mixture of ethers and alcohols, separating them from entrained hydrocarbons and recirculating the latter hydrocarbons through a cracking chamber. 9. A cyclic process for treating saturated hydrocarbons for conversion into valuable synthetic products, including alcohols and ethers with the recovery and recirculation of residuals of the reaction, which comprises cracking said hydrocarbon compounds in a cracking chamber by the application of heat, producing a product containing a plurality of olefins; compressing said product and separating therefrom by liquefaction particular olefins adapted for the production of particular mixed ethers; subjecting said separated particular olefins to the action of H_2O under pressure greater than atmospheric at a temperature above 100 degrees C. in the presence of a catalyst adapted to catalyze hydration reactions in a reaction chamber, forming said mixture of ethers and mixed ethers, the H_2O concentration in said reaction chamber being substantially 2 molecules of olefins to 1 mole.

mole of H_2O , subsequently expanding, cooling and condensing said mixture of ethers and mixed ethers, separating them from entrained hydrocarbons and finally recirculating the latter hydrocarbons through a cracking chamber.

10. A cyclic process for treating saturated hydrocarbons for conversion into valuable synthetic products, including alcohols and ethers with the recovery and recirculation of residuals of the reaction, which comprises cracking aliphatic hydrocarbons having a greater molecular weight than 28 by the application of heat to produce a product containing a plurality of olefins; compressing said product and separating therefrom in known manner a mixture of olefins and saturated hydrocarbons having substantially the same boiling points as said olefins; subjecting said separated olefins to the action of H_2O under pressure greater than atmospheric at a temperature greater than 100 degrees C. in the presence of a solid catalyst adapted to catalyze hydration reactions in a reaction chamber, forming the corresponding mixture of alcohols, the concentration of the reacting substances being substantially in the proportion 2 molecules of said H_2O to 1 olefin molecule; subsequently cooling and condensing said mixed alcohols, separating them from entrained hydrocarbons, and finally recirculating the latter hydrocarbons through a cracking chamber.

11. A cyclic process for treating saturated hydrocarbons for conversion into valuable synthetic products, including alcohols and ethers with the recovery and recirculation of residuals of the reaction, which comprises cracking a plurality of said hydrocarbons in a cracking chamber by the application of heat of such intensity that the resulting products contain an appreciable amount of olefin hydrocarbons along with hydrogen; compressing said products and separating said olefin hydrocarbons from said hydrogen by liquefaction; subjecting said olefin hydrocarbons separated from said hydrogen, while under pressure greater than one atmosphere and at a temperature above 100 degrees centigrade in the vapor phase, to the action of steam in the presence of a solid catalyst adapted to catalyze hydration reactions in a reaction chamber, forming oxygen-containing compounds the compositions of which vary according to the relative concentrations of said steam and said olefin hydrocarbons in said reaction chamber, being chiefly hydroxides when the said relative concentration of steam is great, and chiefly oxides when the said relative concentration of olefins is great; subsequently cooling and condensing said oxygen-containing compounds, separating them from entrained hydrocarbons and finally recirculating the latter hydrocarbons through

a cracking chamber for the further production of olefins.

12. A cyclic process for treating saturated hydrocarbons for conversion into valuable synthetic products, including alcohols and ethers with the recovery and recirculation of residuals of the reaction, which comprises cracking said hydrocarbon compounds in a cracking chamber by the application of heat, forming unsaturates of low molecular weight along with hydrogen; cooling the product thus formed to a temperature below the critical temperature of ethylene, compressing it, liquefying said unsaturates, separating them from the gaseous remainder of said product, heating them, subjecting them while heated and under pressure greater than atmospheric in the vapor phase to the action of steam in the presence of a solid catalyst adapted to catalyze both polymerization and hydration reactions, causing some of said unsaturates of low molecular weight to combine in part, polymerizing to more complex unsaturates, causing said steam to react with both said partially polymerized and unpolymerized unsaturates forming oxygen-containing compounds; subsequently expanding, cooling and condensing said oxygen-containing compounds, separating them from entrained hydrocarbons and conducting the latter hydrocarbons back to a cracking chamber for the subsequent production of additional unsaturates.

13. In the process described in claim 12, the step comprising the simultaneous polymerization and hydration of unsaturated hydrocarbons under pressure greater than atmospheric, at a temperature higher than 100 degree C. in a reaction chamber, by the aid of a mixed catalyst comprising aluminum oxide and at least one salt containing an inorganic acid radical.

14. In the process described in claim 12, the step comprising the simultaneous polymerization and hydration of unsaturated hydrocarbon compounds of low molecular weight by the aid of a catalyst while under pressure greater than atmospheric and at a temperature higher than 100 degrees C. in a reaction chamber forming oxygen-containing compounds of relatively high molecular weight; said catalyst containing both aluminum oxide and a salt containing an inorganic acid radical.

15. A cyclic process for treating saturated hydrocarbons for conversion into valuable synthetic products, including alcohols and ethers with the recovery and recirculation of residuals of the reaction, which comprises cracking said hydrocarbon compounds in a cracking chamber by the application of heat, forming products comprising hydrogen, paraffins and unsaturates, separating some of said paraffins and the olefins separately from the remaining products by compression and

liquefaction, recirculating said separated paraffins through said cracking chamber, compressing them to a pressure greater than atmospheric, heating said separated olefins to a temperature higher than 100 degrees C., introducing them while thus heated and under pressure along with steam into a reaction chamber, causing chemical reaction to occur between them and said steam by virtue of a 5 solid catalyst adapted to catalyze hydration reactions in said reaction chamber, and finally cooling and condensing the reaction products.

16. A cyclic process for treating saturated 15 hydrocarbons for conversion into valuable synthetic products, including alcohols and ethers with the recovery and recirculation of residuals of the reaction, which comprises cracking said hydrocarbon compounds in a 20 cracking chamber by the application of heat at a temperature sufficiently high for substantially complete cracking of paraffins and olefins of high molecular weight, cooling the resulting products, compressing them and 25 separating therefrom ethylene, heating said ethylene and introducing it, while under pressure greater than one atmosphere, and at a temperature higher than 100 degrees C. along with steam into a reaction chamber, 30 causing said ethylene and said steam to react chemically by virtue of a solid catalyst adapted to catalyze hydration reactions forming reaction products comprising oxygen-containing compounds, separating said oxygen-containing compounds from residuals of 35 reaction and recirculating said residuals through a cracking chamber.
